CRUDE OIL PURIFIERS

Floyd A. Kent and Clarence W. Patrick,
Midland, Mich.

Application January 5, 1944, Serial No. 517,293

2 Claims. (Cl. 196—46)

This invention relates to oil purifiers, and more particularly to a machine for treating the crude oil as it is pumped from the wells, thereby breaking up and precipitating the waste, sludge, impurities, and other foreign matter which possesses disagreeable odors, and materially interferes with the cracking and final refining of the product.

One of the prime objects of this invention is to design a machine provided with means for agitating the oil and treating it with absorbents for the purpose of deodorizing and purification.

Another object is to provide a machine including a plurality of disks provided with inclined members thereon, and openings in the disk to permit the passage of the precipitated sludge and foreign matters as the machine is in operation.

A further object is to design a machine of simple, practical, and substantial construction, which can be readily opened and disassembled for cleaning and/or repair, and which in operation, requires a minimum of supervision and attention.

Still a further object is to provide a plurality of outlets at certain predetermined points for draining off the treated oil and also to permit easy removal of sludge and other impurities.

A further object still is to provide a machine of the character described and in which the disks, shaft, and agitating means can be inserted and/or removed as a unit, thereby simplifying the cleaning, repair and/or replacement of parts and the cleaning of the machine proper.

With the above and other objects in view, the present invention consists in the combination and arrangement of parts, hereinafter more fully described, illustrated in the accompanying drawings, and more particularly pointed out in the appended claims, it being understood that changes may be made in the form, size, proportion and minor details of construction, without departing from the spirit, or sacrificing any of the advantages of the invention.

In the drawings:

Fig. 1 is a side elevational view showing our improved machine;

Fig. 2 is a top plan view thereof;

Fig. 3 is an enlarged detail plan showing one of the disks with the agitating means mounted thereon;

Fig. 4 is an edge view thereof; and,

Fig. 5 is a fragmentary sectional view of the disk taken on the line 4—4 of Fig. 4.

Referring now more particularly to the drawings in which we have shown the preferred embodiment of our invention, the numeral 8 indicates the casing or shell of the machine, this is

preferably cylindrical in shape and can be either cast or welded as desired, the bottom being open and a conical shaped section 9 forms a closure for the open end, and is secured thereto by means of bolts 10, a gasket 11 being interposed and forms a leakproof joint as usual. Openings 12 are provided in said conical section 9 to permit the easy and quick removal of sludge or other foreign matter that may collect in the bottom, and conventional gates G form a closure for these openings and are easily and quickly operable.

A cover member 14 forms a closure for the top of the shell and a bearing 15 is provided in the upper end as shown, an end bearing 16 being mounted in the bottom section 9, and a centrally disposed vertical shaft 17 is journaled in said bearings, the upper end projecting beyond the cover, and a pulley 18 is mounted thereon for transmitting power from any suitable source of supply, or an electric motor may be located on the cover to provide an individual drive unit if desired.

A plurality of disk members 19 are mounted on the shaft 17 in spaced apart relation, each disk being formed with a hub 20 to facilitate attachment to the shaft, and a plurality of radially disposed agitating members 21 are provided on the face of each disk, and are welded or otherwise secured in position, openings 22 being provided as shown, and these openings are of predetermined size to permit limited circulation of the oil and precipitation of the sludge as the machine is in operation.

Inlet pipes, lines 23 and 24 respectively are provided as shown, and open into the shell at a point directly adjacent the lower end thereof, the pipe 23 being connected to any suitable source of crude oil supply, and the pipe 24 is connected to a source of water supply. Valves 25 are provided in the lines 23 and 24 for controlling the admission of oil and water to the shell. Similar pipes 26 and 27 respectively are provided adjacent the upper end of the shell, and valves 28 are provided thereon as usual, the pipe 27 opening into the shell at a point below the pipe 26, so that water may be drained as desired, the pipe 27 leading to a suitable tank or other receptacle (not shown), so that as the oil is treated, it can be discharged from the shell through the pipe 27 and into a tank as above described. As the oil is treated, the purified, more volatile oil rises to the top, whereas the sludge, impurities, and other foreign matter precipitates and collects in the conical bottom of the shell and is removed through the gates G when desired.

In practice, the valves 25 are opened to admit crude oil and water to the machine through the pipes 23 and 24, the valves 28 being closed. The shaft 17 is then driven to rotate the disks 19, and the agitators 21 agitate the oil in the shell, breaking up the heavy crude and separating the sludge and impurities which gradually flow through the openings 22 to the bottom of the shell, the clarified, more volatile oil rising to the surface, this oil discharging through the pipe 27 when the valve 28 is opened, and after the machine has been in operation the required period of time, the length of time being dependant on the oil being treated. After the sludge bed has built up in the conical part of the shell, the gates G are opened to permit the removal of noxious sludge and foreign matter, thereby eliminating the odors, after which the gates are again closed for further operation.

For the purpose of aiding the purification and deodorization of the oil as it is treated in the machine, we add certain ingredients, etc. to the crude in the machine, or to the source of crude flow, this however, forms the subject matter of a separate application to be filed by us, and forms no part of the present invention.

From the foregoing description, it will be obvious that we have perfected a very simple, practical, and inexpensive machine for treating crude oil as it flows from the wells.

What we claim is:

1. A crude oil purifier of the class described comprising a cylindrical shell having a conical-shaped detachable bottom section, a vertically disposed driven shaft journaled in said shell and in the conical-shaped bottom section, disks mounted on said shaft in spaced relation and provided with a plurality of radially disposed upwardly inclined agitator vanes secured on the face thereof, intake pipes opening into the lower end of the shell, outlet pipes opening into the upper end of the shell and vertically spaced with relation to each other, openings in the bottom section of the shell, and quickly operable gates forming closures for said openings.

2. A crude oil purifier of the character described comprising a closed shell and including a detachable conical shaped bottom, a vertically disposed, driven shaft journaled in said shell and bottom section, disk members mounted on said shaft in vertically spaced relation and provided with openings of predetermined size in the face thereof, radially disposed, vertically inclined, agitator vanes on the face of each disk, intake pipes opening into the lower section of the shell, outlet openings adjacent the upper end of the shell and vertically spaced with relation to each other, sludge discharge openings in the conical bottom section, and quickly operable gates forming a closure for said discharge openings.
